UNITED STATES PATENT OFFICE.

CLEMENT F. STREET, OF CLEVELAND, OHIO, ASSIGNOR TO THE LOCOMOTIVE STOKER COMPANY, OF WILMERDING, PENNSYLVANIA, A CORPORATION OF PENNSYLVANIA.

MECHANICAL STOKER.

1,130,443.

Specification of Letters Patent. Patented Mar. 2, 1915.

Continuation of application Serial No. 418,837, filed March 2, 1908. This application filed June 7, 1910. Serial No. 565,579.

To all whom it may concern:

Be it known that I, CLEMENT F. STREET, of Cleveland, in the county of Cuyahoga and State of Ohio, have invented certain new and useful Improvements in Mechanical Stokers, of which improvements the following is a specification.

My invention relates to mechanical stokers for feeding fuel to steam boiler fire-boxes, and is designed for the purpose of enabling fuel, in the form of lumps or grains, or what is commercially termed slack, to be projected into the firebox, and to be therein burned on a grate or bed.

My improved stoker is designed with a view of handling coal, coke, briquets or slack, and must be clearly distinguished from that class of stokers designed for handling pulverized or powdered fuel, which is burned in suspension and not on a grate or bed. For convenience, I will make use of the term "lump fuel" hereinafter to designate the kind of fuel to be used in my stoker, in which term I include crushed coal, slack, briquets, and coke.

One of the objects of my invention is to provide improved means for feeding lump fuel of the kind described onto different portions of the grate of any steam-boiler, whether that of a locomotive or of a marine boiler or of a stationary boiler, said means being independent of the usual firing-door, so that hand-firing may be carried on, and the fire be raked when necessary, without interference with the automatic feeding of fuel.

Another object of my invention is to provide a mechanism for the said purpose, which shall be of simple and comparatively inexpensive construction, of such form and dimensions as will render it readily applicable for use on locomotives of the various present standard types, without substantial obstruction of the space within the locomotive cab or interference with the ordinary firing door opening and door, and which shall have the capacity of transferring fuel from the coal space of the tender to the locomotive fire box and distributing it to different portions of the grate thereof.

The improvements claimed are herein-after fully set forth.

In the accompanying drawings, Figure 1

is a rear elevation of a locomotive, equipped with my improved stoker, Fig. 2 is a side elevation, partly in section, of the rear end of the locomotive and the front end of the tender, Fig. 3 is a plan view showing the arrangement of a crusher and its operating motor on the tender, Fig. 4 is a vertical sectional view, on a larger scale, of the devices for controlling the fluid under pressure, Fig. 5 is a vertical section of the controlling cam-disk, taken on the line 5—5 of Fig. 4. Fig. 6 is a side elevation, partially in section, of one of the side distributors. Fig. 7 is an end view of the same. Fig. 8 is a side elevation of the center distributor. Fig. 9 is a cross section of the same, taken on the line 9—9 of Fig. 8, and Fig. 10 is a cross section of the same, taken on the line 10—10 of Fig. 8. Fig. 11 is a vertical section of the elevator and controller driving mechanism.

I have illustrated in the drawings and will now describe one form of apparatus embodying my invention as applied to a locomotive, as that is the application for which the invention has been more particularly designed, but I wish it to be understood that, as far as certain features of my invention, at least, are concerned, it is not limited in its application to locomotives. In this particular embodiment of my invention as applied to locomotives, I provide means for transferring the fuel from the tender to a fuel receptacle located below the deck or floor of the locomotive cab, an elevator for raising the fuel from said receptacle to a point above the firing door or doors, a receptacle or distributor hopper above said door or doors into which the fuel is delivered by the elevator, a plurality of distributors leading from said receptacle or distributor hopper into the firebox, each distributor being provided with a blast nozzle and being constructed to spread the fuel onto a certain zone or area of the grate, which zones or areas may overlap each other, and also being constructed to induce air, a controlling device for varying the frequency and duration of the blasts through the distributors, and means for varying the proportion of fuel delivered to the respective distributors.

The apparatus may also comprise a crusher on the tender for reducing the fuel to suitable size for transmission to and

through the distributers, but such a crusher is not an essential feature of my invention, as the fuel may be, and is preferably supplied to the tender in a properly divided condition.

Referring to the specific instance of application of my invention shown in the drawings, 1 represents the cab of a locomotive, 2 the tender, 3 the boiler, 4 the firebox, 5 the 10 grate, 6 the firing-door opening, 7 a chute for transferring the fuel from the tender to the locomotive, which chute has a pivotal connection with the tender and a sliding connection with the locomotive. In the instance shown, said chute is pivoted at 8 to the bottom of a crusher 9, of the ordinary "jaw" type, a steam-engine or other motor 10, being provided to drive the same. As the crusher is not an essential part of my invention and is only required where the fuel 15 cannot be delivered into the tender in a sufficiently divided condition, it will be unnecessary for me to describe it or its operating means here in detail.

25 The chute 7 leads downwardly and forwardly to a fuel receptacle 11, located below the floor or deck of the cab 1, the fuel being fed down said chute by gravity, but where the conditions are such as to render a gravity feed impracticable or undesirable, a screw or bucket conveyer of any suitable known type, operated by a motor, or from an axle of the tender or locomotive, may be provided in place of the chute. In either 30 case, the feed opening should be preferably on or below the level of the floor of the coal space of the tender.

As shown, the elevator consists of an endless chain of buckets 13, inclosed within a 40 tubular casing, of inverted U-shape, the legs 12, 12, of which terminate in the top of the fuel receptacle 11 and extend upwardly on opposite sides of the firing door 6 and open into a distributer hopper 18, located above 45 said door. The driving mechanism for the chain of buckets 13 consists of a steam engine or other motor 16, mounted adjacent to the top of the casing, and driving through a worm or other gear 17, see Fig. 11, a sprocket 50 wheel 15 which engages said chain. The latter passes around guide wheels 14, 14, mounted in the fuel receptacle 11. As this elevator may be of any suitable well-known construction, it is unnecessary to describe it 55 in further detail.

The elevator delivers the fuel into the distributer hopper 18, to the bottom of which are connected three distributers 19, 19 and 20, which pass through the water-wall 21 of 60 the fire-box 4, the distributer 20 being located centrally above said door and the distributers 19, 19, being located at the sides therof. Where the furnace is of large dimensions, more than three distributers may 65 be used, if desired, while, for a small fur-

nace, only one or two distributers may be employed.

The center distributer 20 is wholly or partially obstructed or closed at its front end, which is provided with a rib 22, located centrally between concavities 21, 21, the end being inclined rearwardly from the top downwardly, as shown in Figs. 8 and 10. Adjacent to its front end, this distributer has lateral apertures 23, 23, which open 75 downwardly and rearwardly toward the grate, the rib 22 being continued along the bottom of the distributer to a point in the rear of said apertures and having inclined sides, as shown in Figs. 8 and 9. Each of the side distributers 19, 19, is open at its front end, the lower side 24 of the opening being raised and straight, as shown in Figs. 6 and 7, and the upper side being extended, as shown, and having at its end a depending 35 lug 25, at right angles to the edge 24 of the lower side of the opening. By the construction described, the center distributer delivers the fuel to the rear portion and rear corners of the grate, while the side distributers feed 90 it straight forward onto the sides of the grate, the lug 25 causing the fuel to be spread somewhat laterally. Of course, the zones of the grate onto which the fuel is deposited by the three distributers, are not 95 finely demarcated, but overlap each other, so that there is a fairly uniform distribution over the entire grate surface.

The rear end of each distributer is provided with two openings, the larger one 27 100 being for the admission of air and the smaller one 28 communicating with a steam-pipe 29, all of which pipes 29 connect with a pipe 30, leading from the steam space of the boiler, through the controlling valve 32, see 105 Fig. 4. Of course, if desired, compressed air may be used instead of steam. The valve proper 31 is normally held to its seat by the steam pressure and by a spring 33, thus shutting off the steam from the pipe 110 30, leading to the pipes 29. The valve is opened intermittently by pressure applied to its stem 34, and this is performed automatically by the cam-disk 35, acting through the lever 36, pivoted on a bracket 37 on the 115 valve-casing, and having a lug 38 bearing against said valve-stem. Cam-disk 35 is driven by the elevator motor 16, in the instance shown being mounted directly on the shaft of the sprocket wheel 15.

120 Rotatably mounted within the cam-disk are two cam-members 39, 39, each having two cam surfaces 40 and 41, the former being of less peripheral extent than the latter, and each having a handle 42, by which they 125 can be rotated to bring either cam-surface into operative position, or so that neither cam-surface will project from the periphery of the disk. To hold each cam-member in any one of said three positions, it is pro- 130

vided with three recesses or notches 44, with any one of which a pawl, consisting of a flat spring 45 with its end bent, can engage.

It will now be understood that the cam-disk, as it rotates, will either open the valve 31 once or twice, and for a longer or shorter time, according as to which cam-surface is projected, or not at all when neither cam-surface is projected. Thus the fluid under 10 pressure can either be cut off entirely from the three distributers, when for any reason it is desired to stop the feed of the fuel by the fluid under pressure, or can be admitted to the distributers once in each rotation of 15 the cam-disk, and that for a longer or shorter duration of time, according as to which cam-surface is projected, or the fluid can be admitted twice in each rotation of the disk, either for two short periods, two long 20 periods or for one short and one long period.

While I have shown and described the cam disk as provided with only two identical cam members, each provided with two cam surfaces of different lengths, it will be 25 obvious that more than two, or only one cam member may be provided on the disk, and that each cam member may have different cam-surfaces from the other, if desired.

A nozzle 46 for the steam or other fluid 30 under pressure is mounted in the opening 28 at the rear end of each distributer. As this nozzle *per se* forms no part of my invention, it will be unnecessary to describe it in detail.

Means are provided within the distributer 35 hopper 18 to vary the proportion of fuel fed to the several distributers. These comprise first, a regulator consisting of a plate 47, slidably mounted in guides 49 in the 40 upper part of the hopper and actuated by a handle 50 outside the same. When this plate is in its innermost position, the fuel is directed toward the opposite side distributer 19 and practically none reaches the adjacent 45 side distributer. Second, of a V-shaped deflector 51, slidably mounted, in guides 52, directly over the open end of the center distributer and operated from outside by a handle 53. When this deflector is pushed 50 in, it prevents the fuel from entering the center distributer and at the same time deflects it laterally toward the side distributers. Of course, when it is partially in, it also acts to deflect the fuel while, at the same 55 time, permitting some of it to enter the center distributer. In this way, the supply of fuel to the individual distributers can be regulated and controlled. It must be understood that the fuel is not stored in the hopper 18, but that the latter acts merely to guide and control the admission of the fuel to the distributers.

In operation, lump fuel is fed into the chute 7 or other conveyer on the tender, being first reduced in size by the crusher 9, if

necessary. From there it passes into the receptacle 11 on the locomotive, from which it is raised by the bucket elevator 13 through one of the legs 12 of the tubular U-shaped casing, and is delivered into the distributer 70 hopper 18, from which it falls by gravity into the three distributers 19, 19 and 20, in amounts and proportion depending upon the adjustment of the slide 47 and deflector 51.

The controller-cam being set to admit blasts of steam or other fluid at predetermined intervals and for longer or shorter periods into the pipes 29, the fuel is intermittently projected from the distributers 80 onto the grate in the manner above described. At the same time, there is no interference with the firing door 6, so that the fireman can attend to the fire and, if necessary, feed fuel into it by hand, as usual. 85

The means for distributing the fuel over the grate area, and comprising the particular form of distributers, and the mechanism for admitting and regulating the admission of fluid pressure thereto, is not claimed in 90 this application, but it is covered in my divisional application Ser. No. 772,513, filed June 9, 1913.

Having thus described my invention, what I claim is:

1. In a locomotive, the combination with the boiler furnace and its firing door, of a mechanical stoker apparatus mounted on the locomotive and comprising a fuel receptacle below the firing floor, an elevator for conveying the fuel from said receptacle to a point above the level of the fuel bed, and means for delivering the fuel therefrom into the furnace. 100

2. In a locomotive and tender, the combination with the boiler furnace, of a mechanical stoker apparatus mounted on the locomotive and comprising a fuel receptacle below the firing floor, means below said floor for delivering fuel from the tender into said 105 receptacle, an elevator for conveying the fuel from said receptacle to a point above the level of the fuel bed, and means for delivering the fuel therefrom into the furnace. 110

3. In a locomotive, the combination with the boiler furnace and its firing door, of a mechanical stoker apparatus mounted on the locomotive and comprising a fuel receptacle below the firing floor, an elevator for conveying the fuel from said receptacle to a 115 point above the said door, and a gravity discharge conduit for delivering fuel from said point into the furnace. 120

4. In a locomotive, the combination with the boiler furnace and its firing door, of a 125 mechanical stoker, apparatus mounted on the locomotive and comprising a fuel receptacle below the firing floor, a conduit located above said door, an elevator for conveying fuel from said receptacle to said conduit, 130

- and a gravity discharge passage leading from said conduit into the furnace independently of the firing door.
5. In a locomotive, the combination with the boiler furnace and its firing door, of a mechanical stoker apparatus mounted on the locomotive and comprising a fuel receptacle below the firing floor, a conduit located above said door, an elevator for conveying fuel from said receptacle to said conduit, and a distributor communicating with said conduit and leading into the furnace independently of said door. 10
6. In a locomotive, the combination with the boiler furnace and its firing door, of a mechanical stoker apparatus mounted on the locomotive and comprising a fuel receptacle below the firing floor, an elevator for conveying the fuel from said receptacle to a point above the said door, and a plurality of gravity conduits for delivering the fuel into the furnace independently of said door. 20
7. In a locomotive, the combination with the boiler furnace, and its firing door, of a mechanical stoker comprising a fuel receptacle located on the locomotive below the firing floor, a tubular casing extending upward from said receptacle on each side of said door, an endless conveyer operating in said casing for raising fuel from said receptacle, and means for delivering fuel from said casing into the furnace. 30
8. In a locomotive, the combination with the boiler furnace, and its firing door, of a mechanical stoker comprising a fuel receptacle located on the locomotive below the firing floor, a tubular casing extending upward from said receptacle on each side of said door to a point above the same, an endless conveyer operating in said casing and receptacle to raise the fuel therefrom, and means for delivering the fuel from said casing above the door into the furnace. 40
- 45 9. In a locomotive, the combination with a boiler furnace having a firing door, of a mechanical stoker apparatus mounted on the locomotive and comprising a fuel receptacle located below said door, a tubular casing extending upward from said receptacle to a point above said door, an elevator operating in said casing to raise the fuel from said receptacle, and means for delivering the fuel from the casing above the door into the furnace.
10. The combination with a boiler furnace having a firing door, of a mechanical stoker comprising a fuel receptacle located below said door, a tubular casing extending upward from said receptacle on each side of said door, an endless conveyer operating in said casing and receptacle to raise the
- fuel therefrom, and means for delivering the fuel from said casing into the furnace. 65
11. In a locomotive and tender, the combination with the boiler furnace and its firing door, of a mechanical stoker apparatus mounted on the locomotive and comprising a fuel receptacle, a distributor hopper located above said door, a power-actuated elevator passing through said receptacle and constructed to elevate the fuel therefrom and deliver it into said distributor hopper, a plurality of distributors leading into said furnace independently of said door, and 70 means to force the fuel out of said distributors into said furnace, and a conduit to convey fuel from the tender into said receptacle on the locomotive. 75
12. In a locomotive, the combination with the boiler furnace and its firing door, of a mechanical stoker apparatus mounted on the locomotive and comprising a fuel receptacle located below said door, a casing located above said door, a power actuated elevator 80 for conveying the fuel from the receptacle into said casing, a distributor leading into the furnace independent of the door, a fuel conduit from said casing to the distributor, and means for forcing the fuel from said 85 distributor into the furnace. 90
13. The combination with a locomotive-boiler furnace having a firing door, of a mechanical stoker comprising a fuel receptacle located on the locomotive below said door, a distributor leading into the furnace independently of said door, a tubular casing extending upwardly from said receptacle, an endless conveyer operating in said casing to elevate fuel from said receptacle and deliver it to the distributor, and means for forcing the fuel through said distributor into the furnace. 95
14. The combination with a boiler furnace provided with a firing door, of a mechanical stoker therefor comprising a fuel receptacle located below said door, a tubular casing extending from said receptacle upwardly on each side of said door, a hopper located above said door with which said 100 casings connect, an endless elevator operating in said casing for conveying the fuel from said receptacle into said hopper, a plurality of distributors leading from said hopper into the furnace independently of 110 said door, and means for forcing the fuel out of said distributors. 115
- In testimony of which I have hereunto affixed my signature in the presence of two witnesses, this 6th day of June, 1910.
